(57) **CLAIM**

The ornamental design for a solar fountain, as shown and described.

DESCRIPTION

FIG. 1 is a front elevational view of a solar fountain; FIG. 2 is a rear elevational view thereof; FIG. 3 is a left side elevational view thereof; FIG. 4 is a right side elevational view thereof; FIG. 5 is a top plan view thereof; FIG. 6 is a bottom plan view thereof; FIG. 7 is a first perspective view thereof; FIG. 8 is a second perspective view thereof; FIG. 9 is a third perspective view thereof; FIG. 10 is an enlarged detail view of area 10 circumscribed within FIG. 7; and,

FIG. 11 is an enlarged detail view of area 11 circumscribed within FIG. 8.

The broken line features and the broken lines and the areas within them depict portions of the solar fountain that form no part of the claimed design.

The dot dash dot broken lines in FIGS. 7-8 and FIGS. 10-11 denote the boundaries of the detail areas and form no part of the claimed design.

The oblique shading lines in the drawings are included to denote the reflective quality of surface planes on the solar fountain.
